STRAND FOR MAKING BRAIDED RUGS AND THE LIKE AND THE METHOD OF MAKING

Application filed September 30, 1931. Serial No. 585,988.

This invention relates to the making of a strand or tape for use in making braided rugs and the like and it has for its object to provide a novel strand or tape which can be made from coarsely woven and relatively inexpensive fabric but which will have the same appearance when woven into a rug as a tape made of relatively expensive finely woven or lustrous fabric.

10 A further object of the invention is to provide a novel method of making a strand or tape of this character.

In carrying out my invention I propose to make the strand or tape from a relatively inexpensive and preferably coarsely woven light weight fabric which may be either plain or dyed in appropriate colors. This fabric is cut into strips of proper width from which the individual strands or tape are made as 15 will be presently described. Either before or after the fabric is cut into these strips it is subjected to a napping operation on one face which raises a pile sufficient to hide or obscure the weave structure. The fabric may be subjected to the napping operation before it is cut into strips or the individual strips may be subjected to the napping operation after they are cut. In either case, one face of the individual strips will have 20 a pile structure sufficient to hide or obscure the weave due to the napping operation.

The strips are made approximately four times the desired width of the completed tape or strand and the strand is formed by first 25 folding the edges of each strip inwardly back on the central portion of the strip until the edges meet in the center, the folding being done so as to place the napped surface on the outside. This makes a two-ply strip one- 30 half the width of the original strip and this two-ply strip is then again folded along a meeting line of the edges of the fabric thereby hiding the raw edges and producing a four-ply strand or tape having smooth 35 rounded edges. This four-ply tape is then braided into a rug or the like in usual way and because of the manner in which the tape or strip is formed the completed rug will have the attractive appearance of a rug made 40 of a braid produced from strands made from

a fine relatively expensive or lustrous fabric.

In order to give an understanding of the invention I have illustrated in the drawing a selected embodiment thereof which will now be described after which the novel features will be pointed out in the appended claims.

Fig. 1 is a view showing the operation of napping the cloth;

Fig. 2 is a fragmentary view illustrating 60 a portion of the strip from which the tape is formed;

Fig. 3 is a view of a section of braid formed from my improved strip or tape;

Fig. 4 shows the operation of folding the 65 strip into the form of a four-ply tape;

Fig. 5 is a view of a section of the folded tape from which the braid shown in Fig. 3 is formed;

Fig. 6 is a view illustrating a mat or cushion 70 made from tape embodying the invention.

The strand or tape embodying my invention is made from a strip 1 of cloth which is a light weight, relatively inexpensive cloth and which may be more or less coarsely woven. One surface of each strip is subjected to a napping operation for the purpose of raising a pile and giving said face of the strip a pile surface sufficient to hide or obscure the weave 75 structure. The strips are cut from a web 2 of cloth and the napping operation may be performed on the web before it is cut into strips or on the strips after they are cut from the web. It will probably be more convenient to perform the napping operation on the web of cloth before it is cut into strips than on the individual strips but the important thing is to provide the strips with a pile face produced by napping one surface of the fabric. 80

The strips 1 are cut with a width approximately four times the desired width of the completed tape or strand and the strand is formed by first folding the edges 3 of the strip back onto the central portion thereof and in such a way that the edges meet along the median line of the strip as indicated at 4. This folding is so performed that the napped surface is on the outside. This produces a 85

two-ply strip, both sides of which present a napped surface. This two-ply strip is then again folded along its median line so as to bring the two previously-folded edge portions 3 together with a face-to-face contact as shown in Figs. 4 and 5.

By this folding operation the raw meeting edges 4 of the strand are entirely concealed within the folded structure and a four-ply strand or tape 5 is provided having smooth rounded or folded edges. One edge 6 of this four-ply strand presents a single fold and the other edge 7 is a double edge formed by the two folded edges 8. During the folding operation the tape will preferably be subjected to pressure to crease the same along the folds 7 and 9 and this creasing operation forms permanent creases at the folds 6 and 8 which serve to hold the four-ply tape or strand in its four-ply folded condition. In the tape or strand thus produced both faces have a pile surface and are thus more or less velvety to the touch. The strand thus has a soft velvety exterior with no raw edge and no weave structure showing and because of the manner in which the strip is folded and creased it will retain its folded condition while being manipulated in forming the braid 9 of which the rug, cushion or other article 10 is made. The soft velvety pile surface of the tape gives it an appearance very similar to that of a tape made from a more expensive firmly woven or lustrous fabric and hence with my invention it is possible to produce from inexpensive fabric a braided rug having an attractive appearance.

While the creasing of the folded strip is regarded as sufficient to maintain the strip in its folded condition while being manipulated yet if desired the folded plies of the tape or strand may be stitched together by a line of stitching running longitudinally thereof. The presence of the stitching, however, is not necessary as by properly creasing the folded tape it will retain its folded condition while being used.

I claim.

1. The method of making a tape or strand for use in braiding rugs and the like, which method consists in subjecting one face of a strip of coarsely-woven light-weight fabric to a napping operation to raise a pile, folding the edge portions of the strip back onto the center portion with the napped surface outside, and with the edges of the strip meeting along a median line thereof and then folding the folded strip along said median line to enclose the edges thereby making a four-ply strand, the exterior surface of which is a napped surface, and creasing the folds formed in the strip thereby to retain the strip in its folded condition.

2. A strand for use in braiding rugs and the like, said strand comprising four plies of coarsely-woven light-weight fabric which

are integrally connected together in a direction transversely of the strand, one edge of the strand presenting a single fold and the other edge a double fold, both sides of the strand presenting a napped surface, and all the folds being creased thereby to retain the strand in its folded condition.

In testimony whereof, I have signed my name to this specification.
